(57) **CLAIM**

I claim the ornamental design for shelving, as shown and described.

DESCRIPTION

FIG. 1 is a front elevational view of shelving showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof; and,

FIG. 7 is a back view showing an alternative embodiment of my new design identical from left, right, front, top and bottom views to the embodiment of FIGS. 1-6 shown and described, and further illustrating the use of hanging ornaments within grooves formed therein, the dashed content of the figure to which no claim is made.
